ATTORNEYS.

UNITED STATES PATENT OFFICE.

ARTHUR WHITE, OF SHEBOYGAN, WISCONSIN, ASSIGNOR OF ONE-HALF TO
CHARLES VAN NOSTRAND, OF SAME PLACE.

KNOCKDOWN FURNITURE.

SPECIFICATION forming part of Letters Patent No. 408,278, dated August 6, 1889.

Application filed July 21, 1888. Serial No. 280,622. (No model.)

To all whom it may concern:

Be it known that I, ARTHUR WHITE, of Sheboygan, in the county of Sheboygan and State of Wisconsin, have invented a new and useful Improvement in Knockdown Furniture, of which the following is a full, clear, and exact description.

My invention relates to knockdown furniture, and has for its object to provide kitchen-safes, wardrobes, or other furniture of this general character, so constructed that the piece of furniture may be set up for use easily and quickly by unskilled persons, and will be very strong and durable in use, and may be packed in knockdown condition in small space for economical handling, storage, or shipment.

The invention consists in certain novel features, of construction and combinations of parts of the knockdown furniture, all as hereinafter described and claimed.

Reference is to be had to the accompanying drawings, forming a part of this specification, in which similar letters of reference indicate corresponding parts in all the figures.

Figure 1 is a front view of a kitchen-safe, in vertical transverse section, taken on the line *x x* in Fig. 2. Fig. 2 is a vertical sectional end or side view taken on the line *y y* in Fig. 1; and Figs. 3, 4, 5, 6, and 7 are enlarged detail sectional views, to be hereinafter referred to.

My invention relates more particularly to the manner of holding the fronts and backs of kitchen-safes or wardrobes or like articles of furniture to the end parts thereof. The drawings represent a kitchen-safe embodying the invention, and in reference to which I will particularly describe the improvements.

The kitchen-safe, like many articles of furniture, is made with a front A, a back B, and opposite ends C C, which may have any desired relative proportions. I show the safe provided with upper doors *a'* and lower doors *a* in its front, and with a couple of drawers D D fitted a little below the center of the safe and between the doors, while above the drawers the safe is provided with a sliding shelf E, which may be pulled out to serve as a bread-board or as a receptacle for tempora-

rily holding articles of food for use, or substances removed from or to be put into the safe, the shelf thus serving to increase the capacity of the safe. The shelf may be fitted below the drawers in safes of other proportions or design, and in any case will be a desirable and useful adjunct of the piece of furniture.

The ends C C of the safe may have either a solid or paneled construction, and the panels 60 may be perforated or imperforate, and may be made of wire-gauze material in any approved way; and the front and back of the safe may likewise be fitted with solid or perforated panels of any design, as my method 65 of uniting the front, back, and ends of a piece of furniture of this general character interferes little or none with the adoption of any preferred exterior design or construction.

For connecting the front, back, and ends of the safe, I employ cross-bars F, which may have any cross-sectional form, but which are preferably round, as shown, and are provided with dovetail-shaped tenons f f, which also are preferably round, and are formed one at 75 each end of each cross-bar, which thus are provided with shoulders f' next the tenons. These cross-bar tenons f are adapted to enter recesses or mortises G H, made, respectively, in the front and back of the safe. The recess 80 G, which is shown in the safe-front A, is made with an upper portion g large enough to admit the extremity of the dovetail tenon f at one end of a cross-bar F, and the lower part g' of the recess is contracted toward the inner face of the front, or is in dovetail shape, so that when the tenon falls or is pushed into it the cross-bar will firmly lock with the safe-front. The recess H, which is shown in the safe-back B, is made gradually deeper from 85 its upper broader end to its lower narrower end—in other words, the width of the recess is the same at its back wall, but at the face of the safe-back the recess gradually becomes narrower toward its lower end or portion, 90 which thus has a dovetailed form in horizontal section, which corresponds to the form of the tenon f of a cross-bar F, which may be slipped into the top of the recess H and then be pushed down into the recess, so as to lock 100

with the safe-back. The ends C C of the safe are provided with dowels c, which are adapted to holes made for them in the front and back of the piece of furniture. With this construction it is obvious, when the front and back A B are set against the ends C C, the dowels c of which enter the parts A B, that one end tenon f of the cross-bars F used in the piece of furniture may be set directly into the larger part g of the recess G of the front A, and the cross-bar, when in the inclined position indicated for one bar in Fig. 2 of the drawings, may then readily be entered into the gradually-deepening opposite recess H; and may then be pushed down to the bottoms of both the recesses G H, to interlock securely with the safe front and back, which will be in contact with the cross-bar shoulders f' at the bases of the tenons f, and the front and back cannot pull away from the cross-bar. As the end dowels c enter the holes in the front and back A B, the ends C C will thus be locked securely to the front and back, and when all the cross-bars F are in place the entire structure will be held together in a most substantial manner, and the cross-bars will form firm rests or supports for the shelves I of the safe or wardrobe. The cross-bars F would by their end tenons f rest in the contracted lower parts of the front recesses G; but as a safeguard against slipping upward of the tenons in these recesses pins J may be set into the corner-posts a of the front above the tenons, as shown in Figs. 2, 4, and 5 of the drawings. Figs. 4 and 5 of the drawings illustrate the fit of the cross-bar tenons in the recesses G of the safe-front A, and Figs. 3, 6, and 7 show how the cross-bar tenons enter the recesses H of the back B of the safe.

I prefer to make the cross-bars F round and with round tenons, because they may be more cheaply made in this than in other form, and they may be more quickly and easily fitted to the safe front and back by unskilled workmen, as the tenons will always freely en-

ter the recesses G H, however the cross-bars may be held when assembling the parts of the piece of furniture.

It is obvious that by using cross-bars F having dovetail tenons, and providing recesses 50 in the front and back A B to receive the tenons, substantially as above described, the corner posts or pieces a b of the parts A B may be made very much thinner than would otherwise be allowable, and thus will promote 55 economy in first cost of the piece of furniture, and will also allow it to be packed in much smaller space than would otherwise be possible for economical storage or for shipment in "knockdown" condition, as projecting cleats 60 on the safe or wardrobe ends for supporting the shelves are dispensed with, and the tenoned cross-bars may be stowed away in the drawers of the safe or wardrobe, and thus occupy little or no packing-space. 65

Any one or more of the shelves I may be removed at any time from the set-up piece of furniture, as will readily be understood.

Having thus described my invention, what I claim as new, and desire to secure by Letters 70 Patent, is—

1. Knockdown furniture made with front and back portions provided with dovetail-shaped recesses, combined with round cross-bars having round dovetail-shaped end tenons 75 adapted to said recesses, substantially as herein set forth.

2. In knockdown furniture, the combination, with a front A and back D, of opposing recesses G H in said parts, said recesses G 80 having a contracted dovetail-shaped lower portion g', and the inclined recesses H, having a contracted and dovetail shape at the lower portion, and cross-bars F, having dovetail end tenons f fitting said recesses, substantially as herein set forth. 85

ARTHUR WHITE.
